METHOD AND APPARATUS FOR MAKING AUTOMOBILE DOOR PANELS Ralph E. Woodburn, Southfield Township,
Oakland County, Mich.

Application October 22, 1952, Serial No. 316,285

17 Claims. (Cl. 154—41)

This invention relates to an improved upholstered panel for automobile bodies and more particularly for the inside surface of automobile body door, and an improved method and apparatus for making such panel.

The value of a modern passenger automobile is greatly enhanced by the appearance of its exterior as well as interior. Strenuous efforts of automobile body designers are directed not only toward improving the exterior appearance of an automobile but also to make the interior thereof, including its upholstery, more luxurious and pleasant looking, preferably without adding appreciably to the cost of the vehicle.

One of the instances to which efforts of body designers are directed is the inside surface of automobile doors under the glazed portion thereof, which surface is of considerable area and invites provision of a pleasing ornamental design. Ornamental hardware for the window regulators and door locks are provided on this surface and various ornamental designs are usually incorporated into the upholstery of this surface. Upholstering of this surface is usually done by connecting to it an upholstered panel that may be separately produced and upholstered and thereupon attached to the inner side of the door in one of the several methods well known in the art.

The ornamental designs usually employed for these panels include beaded or striped portions, which portions are often provided on separate smaller panels assembled to the door panel.

Provision of beaded panels or portions is connected with considerable manufacturing difficulties. The usual way of providing such beaded portions is to cover a panel with a matted material, covering the mat with a suitable upholstery material and stitching the upholstery and the mat to the base of the panel with the use of a sewing machine, providing a number of parallel seams thereon. In the process of sewing, the mat is compressed along the seam and is stitched to the cardboard, while the portion of the mat between the seams remains uncompressed and therefore extends or bulges away from the base, thus providing appearance of a raised bead.

Another common method of providing such beaded panels is to provide first a cardboard or fiber board base and to secure to it a number of strips of similar material, and thereupon to cover the entire panel with an upholstery cloth, with stitching of the cloth to the cardboard base at the grooves formed between the strips.

It has been found, however, that in both of the above described expedients, matting and stitching of the panels is a rather annoying and expensive operation not always producing desired results. It has been appreciated, for instance, that when stitching is used on panels in which the cores of the beads are formed by strips of cardboard or similar material, stitching of the material results in its stretching over such strips and producing relatively sharp corners which, in turn, cause shallow or flat appearance of the panel; moreover, such undesirable stretching often distorts the weave or pattern of the upholstery cloth or the ornamental design provided on the material. In addi-

2

tion, the stretching condition of the cloth in the grooves creates a tendency in the material to return to its original unstretched condition unless it is held in the groove by some permanent means such as the seam itself. However, should any of the threads of such a seam become broken, the material pulls itself out of the grooves, destroying the desired appearance of the panel.

Attempts have been made to use forming dies with ribbed surfaces, with the ribs being intended to push the upholstery material into the grooves. However, it was found that such an expedient is suitable only for producing panels having impractically shallow grooves, since when grooves of proper depth were attempted to be formed with the aid of such dies, the upholstery material was overstretched and broken, or at least so badly destroyed as to make such panels unsuitable for use in automobile bodies.

One of the objects of the present invention is to provide an improved door panel and a method and machine for manufacturing the same, whereby the above difficulties and disadvantages are eliminated and improved beaded panels are produced in a greatly superior manner.

Another object of the present invention is to provide an improved automobile door panel including beaded portions, in which the upholstery material covering the beads is laid into the grooves between the beads without being stretched in the process thereof and therefore remains in the groove without the material showing a tendency to pull itself out therefrom.

A further object of the present invention is to provide an improved door panel including beaded portions, which panel may include a relatively hard base strip for the beads and yet when covered with upholstery cloth presents a full and rich appearance without distorting the weave of the cloth, showing sharp corners of the base strips, and flattening the entire design, thus imparting to it an inferior appearance.

A still further object of the present invention is to provide an improved method and a machine for producing beaded upholstered panels, particularly panels for automobile doors, whereby the beaded portions of the panel are produced in a simple and inexpensive manner, with the panels so produced presenting full and rich appearance in spite of inexpensive materials that may be used.

A still further object of the present invention is to provide an improved machine of the nature specified in the preceding paragraph, which machine operates to cure the cement of the upholstery material to the base of the grooves in the process of laying the material therein.

A still further object of the present invention is to provide an improved method and machine for covering beaded panels with upholstery cloth, whereby the cloth may be applied to panels having grooves of such a depth that use of any conventional method and machines would be totally impracticable.

A still further object of the present invention is to provide an improved machine for making upholstered panels for automobile doors including beaded portions, and particularly for covering said beaded portions with an upholstery material, which machine can be easily adapted or changed to cover such panels having various designs or arrangement of beads.

It is an added object of the present invention to provide an improved automobile door panel and a machine for making the same, which are simple in construction, dependable in operation and relatively inexpensive to manufacture and to maintain.

Further objects and advantages of this invention will be apparent from the following description and appended claims, reference being had to the accompanying drawings forming a part of this specification, wherein like ref-

erence characters designate corresponding parts in the several views.

Fig. 1 is a perspective view showing an automobile door upholstered panel including a beaded portion made in accordance with the present invention.

Fig. 2 is a perspective view showing on an enlarged scale the beaded sub-panel or the beaded portion separately.

Fig. 3 shows a cardboard base for the panel of Fig. 2 having glue applied to it for securing the bead material sheet thereto.

Fig. 4 shows the method and the apparatus for cutting the grooves in the bead material sheet between the glued portions thereof and cutting out narrow strips from the bead material sheet, thus producing grooves and beads 15 in the panel base.

Fig. 5 shows the base for the panel before the same is covered with upholstery cloth.

Fig. 6 is a sectional view illustrating the method of covering the beaded panel base with a substantially unstretched upholstery material.

Fig. 7 illustrates diagrammatically a portion of a machine for producing a 5 beaded panel.

Fig. 8 is a side view of a complete machine constructed in accordance with the present invention.

Fig. 9 is an end view of the machine of Fig. 8.

Fig. 10 is a top view of the machine of Figs. 8 and 9.

Fig. 11 is a plate sub-assembly for making a 12 bead panel with a different width of beads, which sub-assembly can be substituted in the machine of Figs. 8-10 for the corresponding sub-assembly adapted for making a 5 beaded panel.

Figs. 12, 13 and 14 illustrate modified methods and machines of a modified construction contemplated by the present invention with the groove-forming plates thereof being shown in their raised or fully retracted positions.

Figs. 12a, 13a and 14a illustrate, respectively, the machines of Figs. 12, 13 and 14 but showing their bead-forming grooves in their fully raised or retracted position.

It is to be understood that the invention is not limited in its application to the details of construction and arrangement of parts illustrated in the accompanying drawings, since the invention is capable of other embodiments and of being practiced or carried out in various ways. Also it is to be understood that the phraseology and terminology employed herein is for the purpose of description and not of limitation.

In accordance with the invention I provide an improved method and machine for manufacturing beaded upholstered panels and particularly such panels as are used in automobile doors. The present invention contemplates making, in an improved manner, the beaded panel base as well as application of upholstery material for covering the panel, and particularly of upholstery materials which are substantially unstretchable such as fabrics, oilcloth, imitation leather, and the like. In making the beaded panel base I discard the conventional practice of glueing to the cardboard or fiber sheet the strips that form cores for the beads, since aligning such beads is a very tedious job not always producing proper arrangement of the beads. I glue to the cardboard or fiber sheet another full sheet of beading material, the glue being applied to either of the sheets in streaks or lines to provide glue only between the sheets in places where the beads are located, but to have no glue in places of grooves. After two sheets are thus glued together, I cut out strips of the beaded material equal in width to the width of the grooves, thus forming such grooves when these strips are removed.

In applying upholstery material to the beaded panel base, which material is usually unstretchable, I discard the former practice of sewing down such material or forcing such material into the grooves with the aid of conventional forming dies. In accordance with the invention I push this material in with the aid of a number of

independently slideable plates or blades in a successive manner, one bead after another, thereby permitting the material to be drawn from one side to compensate for the amount of material pushed into the last completed groove, thereby covering the entire panel without stretching the material. Grooves of virtually any practicable depth may be produced with the aid of my improved method, such for instance, as grooves up to one inch or even more deep, as may be desired in upholstering seat cushions, and in similar applications.

In accordance with the invention I also provide a machine in which there is provided a work table adapted to receive and locate the panel and a sliding plate assembly with the plates intended to operate as explained above to cover with upholstery material a beaded panel of a predetermined type. The plate sub-assembly has to be changed for different types of beaded portions of door panels. Heating means are provided to heat the plates and thus to apply heat at the grooves of the panel to produce a more secure glueing or cementing of the material thereunto.

In accordance with the invention forming of the grooves may begin either at one extremity of the panel and proceed from one extremity thereof to the other, or it may be commenced at the middle portion thereof, and proceed toward the extremities thereof.

The machine contemplated by the present invention may be of a mechanical nature using cams, springs, levers or similar means, or they may be of a fluid-operated type, pneumatic or hydraulic.

In the drawings there is shown by way of example a panel manufactured in accordance with the present invention and apparatus for making the beaded panel base, as well as a machine for covering the bead panel base with upholstery material.

Referring specifically to the drawing, Fig. 1 illustrates an automobile door panel generally designated by the numeral 15 and made in accordance with the present invention.

Said door panel 15 has provided therein an ornamental beaded panel portion 16. In the door panel illustrated, said portion 16 is made as a separate piece and is thereupon inserted in its place in the panel 15. The panel portion 16, shown separately in Fig. 2, comprises the base sheet 17 of cardboard, fiber, or a similar sheet material, to which there are connected in any suitable manner such as by glueing or cementing, a plurality, in the present instance five, of strips 18 extending parallel to each other and having grooves such as 19 provided between them. The panel 16 is covered with a substantially unstretchable upholstery cloth, generally designated by the numeral 20, which cloth is wrapped over the edges of the panel as shown at 21 and is secured thereto on the back side of the panel by glueing, cementing, stapling, or in any other suitable manner.

The cover material 20 is pressed into depressions or grooves 19 without stretching the material. By virtue of such an expedient the ornamental design provided on the upholstery material, or the weave of the cloth thereof or other surface ornamentations that may be provided thereon, are not distorted. Moreover, the material 20 is arranged in the grooves 19 by pushing it therein against negligible resistance, and therefore it wraps the beads without being so tightly drawn around the same as to show sharp corners of the bead bases through the upholstery material, but on the contrary presenting full and rich appearance. By virtue of such an expedient my improved automobile door panel in spite of the use of less expensive materials presents a greatly superior appearance than conventional automobile door beaded panels usually do, and it retains its beaded design for a much longer period of time.

Making of my improved automobile door beaded panel comprises generally two main processes: first, making of the beaded panel base as illustrated in Figs. 3, 4 and 5,

and second, covering the beaded panel base so produced with a substantially unstretchable upholstery cloth in a manner illustrated in Figs. 6 and 7.

In accordance with the invention I first provide a base sheet 17 which may be produced by stamping operations, preferably with the use of the rule dies. Thereupon, I apply glue to the sheet 17 in lines or streaks, such as indicated at 25 in Fig. 3, preferably using glueing rollers. Thereupon, I place over the sheet 17 a sheet of bead material generally designated by the numeral 26, causing the sheet 26 and the sheet 17 to be glued together in places where the beads are to be produced, but not where the grooves are intended to be.

Thereupon, the assembled sheets are operated upon in a machine illustrated in Fig. 4 and including two cutting circular blades or rollers 27 which are rolled with pressure applied to them to cut strips such as 28 between the glued portions 25 and in places where grooves or depressions between the beads are to be produced. After the cut out strips 28 are removed, the base panel acquires beaded appearance as illustrated in Fig. 5.

Applying the upholstery cover sheet 20 to the beaded panel base is illustrated in Figs. 6 and 7 and is done with the aid of independently sliding plates or blades 30. A very important feature of my improved process resides in the fact that the plates 30 are not applied simultaneously as are the ribs of forming dies previously used, but are moved independently and applied successively, one by one, with one of the plates being pushed all the way down into the groove, such as shown in Figs. 6 and 7, before the next plate contacts the cover sheet 20.

For application of the blades, the sheet 20 is arranged on the beaded panel base with one of its side edges substantially aligned with the edge 17a of the panel with sufficient overlap to wrap it over under the edge of the panel, as shown at 21. With the edge 21 being thus held to the panel, the first plate 30 is applied to the sheet 20 to push the upholstery material all the way down into the groove 19, in consequence whereof the upholstery material is pulled from the lefthand side as indicated by arrow in Fig. 6, compensating for the amount of material pushed into the groove. The second plate 30 is now ready to contact the upholstery material and to push it into the second groove. With the second plates being in place as indicated in Fig. 7, the third plate 30 is now ready to be pushed into the third groove, repeating the cycle. When the third plate is pushed all the way down into the groove, the last or fourth plate is applied to the cloth in a similar manner. As the plates 30 are being pushed down into their respective grooves, the cloth 20 is moved in steps from the lefthand side of the upholstery material base until all the plates are in place. It should be noted, that until the previously actuated plate is all the way down, the next plate should not exert any pressure on the upholstery material.

It is preferable to apply some glue or cement to the bottoms of the grooves 19, which may be done with the aid of suitable wheels or rollers, and to have the plates 30 heated to a predetermined temperature. With the plates 30 being heated and held in place in the grooves, the glue sets within a very short period of time, such as one or two minutes, depending on the material and the glue. Thereupon, the plates 30 are removed from the grooves, and the panel is completed by wrapping the edges of the upholstery material around the base sheet and connecting them thereto, as mentioned.

One form of the machine for application of the substantially unstretchable upholstery material to the beaded panel base and thus carrying out the method disclosed above is illustrated in Figs. 8-11. Fig. 7, although used for illustrating the method explained above, is, in effect, also a diagram illustrating the action of the machine of Figs. 8-11, and therefore, the same numerals are applied in said figure to the parts thereof corresponding to those of the machine of Figs. 8-11.

Referring specifically to Figs. 8-11, the machine illustrated therein comprises a frame including four standards 35 and upper horizontal members 36 connecting said standards together. Lower horizontal members 37 support a work table 39 adapted to receive and to locate the work panel with respect to the sliding plates 30. Locating of the panel on the work table 39 may be effected with the aid of corner stops, pins, or similar means. The sliding plates 30 are arranged to have their ends slide in end guide boards 40, while their intermediate portions slide in guides 41 adapted to prevent side buckling of the plates 30 and to hold them together. The horizontal members 37, the work table 39, the plate guides and the plates themselves are thus connected together and form a sub-assembly which may be removed and inserted into the machine as a single unit.

The plate sub-assembly comprises a plurality, in the present instance four, of metal plates or blades 30 vertically slidable in guides 40 and 41, as mentioned. Springs 45, two for each of the plates 30 at both ends thereof, are provided, each of said springs having a lower end connected to the top of the plate 30 and an upper end supported on the bar 46 which is, in turn, supported on the frame of the machine. Electrical heating means, such as heating elements 47, are provided on each plate. Elements 47 preferably extend throughout the entire length of each plate near the lower edge thereof to provide for uniform heating of the lower edge of the plate. Thermostatic means 48 are provided on each plate 30 to control its heating element 47 and thus to maintain the plate 30 in a predetermined temperature.

It will now be seen in view of the foregoing that when the upper ends of the springs 45 are disconnected from the bar 46, the plates with their guides and heating means, together with the working table 39 and the guides 40 and 41, may be removed from the machine and stored as a unit similarly to die apparatus including the punch and die portions. Thereupon another set of plates and work table such as illustrated in Fig. 11 and designed for a panel with different character of beads may be inserted in the machine and connected thereto with the aid of suitable bolts for performance of another job.

Means are provided to push down the plates 30 successively, that is, one bead after another. In the present embodiment said means are of the cam type and comprise a slidable ram slidable horizontally but restrained from upward movements. The ram includes cam bars 50 having two straight portions 51 and 53, and a cam portion 52 arranged between said straight portions. When the ram is in a position to have its straight portion 53 contact the top edges of all of the plates 30, it operates as a stop therefor with springs 45 keeping the plates in their uppermost position. If the ram is moved to the left, its cam portion 52 contacts plates 30 and pushes them one after another into the grooves 19. When the cam bars 50 are all the way to the left and their straight portions 51 contact the upper edges of the plates 30, said plates 30 are held down in the grooves for the purposes explained above. Moving the ram with its bars 50 all the way to the right, releases plates 31, one after another, and permits them to come all the way up until they are stopped by the straight portion 53.

Means are provided to move the ram with its cam bars 50 in a desired manner. In the present embodiment of the invention said means are exemplified by a rack 55 secured to the ram of which the bars 50 form the side members and cross bars 56 form the end members. A pinion 57 secured to the shaft 58 engages the rack 55. The shaft 58 is journaled in bearings 59, as is best shown in Figs. 9 and 10. A handle 60 is provided on the free end of the shaft 58. When the shaft 58 is rotated, which in the present embodiment of the invention is done manually with the aid of the handle 60, the ram moves to the right or to the left, as desired, pushing the plates down or per-

mitting the springs 45 to pull them up into their uppermost or retracted position.

It will be understood that means actuating the plates may be of the cam type as well as of other types, such as hydraulic or pneumatic cylinders operating either individual plates or cam or lever means acting on the plates.

It will also be understood that while the present embodiment of the machine shows means pushing the plates from one side of the bead assembly to the other, said plates may be pushed from the middle of the material toward both of the edges thereof. With such an expedient, particularly useful when the number of the beads is large, the operation may be performed much faster.

Machines of such a nature are shown in Figs. 12, 13 15 and 14.

Referring particularly to Figs. 12 and 12a, the machine illustrated therein utilizes a plurality, in the present instance six, of substantially identical springs mounted on the ram 61. The springs are designated in pairs by numerals 62, 63 and 64. Spring plungers 62a, 63a and 64a of different lengths are provided to prevent said buckling of the springs, and to have them normally compressed to different lengths, with springs 62 being least compressed and extending downwardly to a further distance, while the springs 63 and 64 are compressed to shorter lengths as illustrated.

By virtue of such a construction, as the ram 61 is moved down, the two spring-pressed plungers 62a contact the two middle plates 65 and push them down into the grooves of the panel 66 arranged on the table 67. When the plates 65, 65 are all the way down in their grooves the spring-pressed plungers 63a contact plates 68, 68 and also push them all the way down. Thereupon, the plates 69, 69 are similarly contacted by the spring-pressed plungers 64a and also brought all the way down, bringing the plate assembly into the condition illustrated in Fig. 12a.

It is preferable to have the springs of substantially similar dimensional and rate characteristics, and to have the plungers of the different lengths, as illustrated.

The plungers may be in the form of bolts, with their bolthead operating on the plates, and their operative lengths determined by the position of two jam nuts carried by their threaded ends. Washer plate 61a may be used if desirable. By virtue of such a construction successive contacting of the plates will be achieved and, in addition, when all of the plates are all the way down, a substantially uniform pressure is exerted on all of the plates as can be understood from examination of Fig. 12a, since in the positions illustrated in said figure all of the springs are uniformly deflected. It will be understood that all of the springs should have sufficient rate i. e. "be stiff enough" even in the positions of springs 63, 63 in Fig. 12 to actuate the plates against all operational resistances.

Fig. 13 illustrates a construction in which successive application of the plates 70 thereof is attained with the aid of a toggle linkage 71 normally maintained in its fully extended position by the action of the spring 72. The spring 72 is stiff enough to cause movement of the two middle plates, but is compressed as the ram 73 moves downward. As the spring 72 is compressed, the toggle linkage 71 contacts the next two plates and, finally, the extreme two plates and comes into a condition illustrated in Fig. 13a, where further pressure on the ram 73 exerts substantially uniform pressure on all of the plates 70.

Fig. 14 illustrates a machine in which the plates thereof, generally designated by the numeral 80, are actuated with the aid of fluid-operated means. In the construction illustrated, there is provided a plurality of fluid-actuated (pneumatic, hydraulic, or steam) cylinders corresponding in number to that of the plates. The cylinders are designated in the drawing by the numerals 81, 82, 83, 84, 85 and 86. Within said cylinders there are slidably-fitted double-acting pistons having rods 81a, 82a, 83a, 84a, 85a

and 86a respectively, connected to their respective plates. The pressure conduit 87 is connected by branch conduit 88, 89 and 90 to each of the three pairs of cylinders with valves 91, 92 and 93 controlling said branch conduits respectively. Each of the branch conduits 91, 92, and 93 is branching into two conduits, as shown. The opposite sides of the cylinders are connected to a conduit 94 controlled by a single valve 95.

In operation, by opening the valve 93 the fluid under pressure is admitted into the cylinders 83 and 84 causing them to push the two middle plates downward. Thereupon, by opening the valve 89 the cylinders 82 and 85 are similarly operated, and finally by operating the valve 91 the cylinders 81 and 86 are also operated, pushing the extreme plates downwardly and thus bringing the device into the condition illustrated in Fig. 14a.

For withdrawing the plates, the valve 95 is open for admission of pressure into the conduit 94 with simultaneous closing of the pressure valve 96 and opening the exhaust valve 97 to permit exhaust of the steam from the opposite sides of the cylinders.

By virtue of such a construction withdrawing of all of the plates is done quickly and simultaneously.

If steam is used, it may also be utilized for heating the plates which may be made hollow or jacketed as desired.

I claim:

1. The method of making a vehicle body door upholstery panel including a number of beads covered with upholstery material, said method including the steps of providing a panel base with raised portions forming cores for the beads and having grooves therebetween, arranging the upholstery cover material over said panel base and pushing said upholstery cover material into the grooves in successive arrangement, the material being pressed down into one groove first and then progressively pressed down into the adjacent and successive grooves, the pressing down being accomplished in one groove at a time, rather than in a simultaneous pressing down operation.

2. The method of making an automobile body upholstery panel including a number of beads covered with upholstery material, said method including the steps of providing a beaded panel base having depressions between the beads, applying the upholstery cover material to said panel base by pushing said material into the depressions starting with two adjacent depressions and proceeding therefrom in a successive arrangement to press the material down into the adjacent and successive grooves one after the other, the pressing down being accomplished substantially in one groove at a time rather than in a simultaneous pressing down operation.

3. The method of making an automobile body upholstery panel including a number of beads covered with upholstery material, said method including the steps of providing a flat piece of substantially rigid base material, applying glue to said flat base piece only in places where beads are to be located, placing a piece of bead core material over the glued surface of the base piece, cutting out and removing strips of said bead core material in places where grooves are desired to produce a beaded panel base, applying upholstery cover material to the beaded panel base by pushing said material into the grooves in successive arrangement, the material being pressed down into one groove first and then progressively pressed down into the adjacent and successive grooves, the pressing down being accomplished in one groove at a time rather than in a simultaneous pressing down operation.

4. The method defined in claim 3 and including applying glue into the grooves after the same are cut out and before the beaded base is covered with the upholstery cover material, to fix the upholstery material in the grooves.

5. The method of making an automobile body uphol-

stery panel including a number of beads covered with upholstery material, said method including the steps of providing a flat piece of substantially rigid base material, applying glue to said base piece only in places where beads are to be located, placing a piece of bead core material over the glued surface of the base, cutting out and removing strips of said bead core material in places where grooves are desired, to produce a beaded panel base, covering the beaded base with a piece of upholstery cover material and pressing said material into the grooves successively one adjacent groove after another toward the end of the beaded portion, with the upholstery material at said end being left free to move bodily toward the groove wherein pressing in of the material takes place.

6. The method of making an automobile body upholstery panel including a number of beads covered with upholstery material, said method including the steps of providing a flat piece of base material, applying glue to said piece only in places where beads are to be located, placing a piece of bead core material over the glued surface of the base, cutting out and removing strips of said bead core material in places where grooves are desired, to produce a beaded panel base, covering the beaded base with a piece of upholstery cover material operatively aligning one edge of the material with one end of the panel, and pushing the upholstery material into the grooves between the beads starting with the groove at said aligned edges and progressing successively from one adjacent groove to another toward the opposite end of the panel, the pressing down being accomplished substantially in one groove at a time rather than in a simultaneous pressing down operation.

7. A machine for applying upholstery material to beaded base panels, said machine comprising a work table adapted to receive a work panel and to locate the same, a plurality of individually slidable plates having work edges adapted when actuated to push the upholstery material into depressions between said beads when the work panel is located to have said depression aligned with respect to said plates, and means to actuate said plates successively to have the previous plate bring the upholstery material all the way to the bottom of the respective depression on the beaded base panel before the next plate contacts the material over the next depression.

8. A machine for applying upholstery material to beaded base panels, said machine comprising a work table adapted to receive a work panel and to locate the same, a plurality of individually slidable plates having work edges adapted when actuated to push the upholstery material into depressions between said beads when the work panel is located to have said depression aligned with respect to said plates, and mechanical means adapted to actuate said plates successively to have the previous plate bring the upholstery material all the way to the bottom of the respective depression on the beaded base panel before the next plate pushes the material into the next depression.

9. A machine for applying upholstery material to beaded base panels, said machine comprising a work table adapted to receive a work panel and to locate the same, a plurality of individually slidable plates having work edges adapted when actuated to push the upholstery material into depressions between said beads when the work panel is located to have said depression aligned with respect to said plates, and means to actuate said plates successively to have the previous plate bring the upholstery material all the way to the bottom of the respective depression on the beaded base panel before the next plate begins to push the material into the next depression, means to heat said plates, and means to hold said plates in said depression for a desired period of time.

10. A machine for applying upholstery material to

beaded base panels, said machine comprising a work table adapted to receive the work panel and to locate the same, a plurality of slidable plates having work edges adapted when actuated to push the upholstery material into depressions between said beads when the work panel is located to have said depression aligned with respect to said plates, and means to actuate said plates successively to have the previous plate bring the upholstery material all the way to the bottom of the respective depression on the beaded base panel before the next plate begins to push the material into the next depression, electric means to heat said plates, thermostatic means adapted to control said electric means to maintain said plates at a required temperature, and means to hold said plates in said depression for a desired period of time.

11. A machine for applying upholstery material to beaded base panels for automobile doors, said machine comprising a plate sub-assembly including a plurality of plates corresponding in their thickness and arrangement to those of the bead-determining depressions on the work panel, means to support said sub-assembly in the machine, resilient means to maintain the plates in their retracted positions, a work-table adapted to receive the work-panel and to locate it with respect to said plates, and cam means adapted to actuate said plates successively one by one into said panel depressions to push the upholstery material thereinto, and to hold said plates in said depressions at least until all of the plates are in their retracted positions.

12. A machine for applying upholstery material to beaded base panels for automobile doors, said machine comprising a plate sub-assembly including a plurality of individually movable plates corresponding in their thickness and arrangement to those of the bead-determining depressions on the work panel, means to support said sub-assembly in the machine, resilient means to maintain the plates in their retracted positions, a work table adapted to receive the work panel and to locate it with respect to said plates, cam means adapted to actuate said plates successively one by one into said panel depressions to push the upholstery material thereinto, and to hold said plates in said depressions at least until all of the plates are in their retracted positions, electric means to heat said plates, thermostatic means to control said electric means to maintain said plates at a predetermined temperature.

13. The machine defined in claim 11, said plate sub-assembly being insertable and removable therefrom as a unit.

14. A machine for applying substantially unstretchable upholstery material to beaded base panels, said machine comprising a work table adapted to receive a work panel and to locate the same, a plurality of individually slidable plates having work edges adapted when actuated to push the upholstery material into depressions between said beads when the work panel is located to have said depression aligned with respect to said plates, and springs preloaded to progressively decreased lengths and adapted to actuate said plates successively, to have a plate bring the upholstery material all the way to the bottom of the respective depression on the beaded base panel before the next plate pushes the material into the next depression.

15. A machine for applying upholstery material to beaded base panels, said machine comprising a work table adapted to receive a work panel and to locate the same, a plurality of individually slidable plates having work edges adapted when actuated to push the upholstery material into depressions between said beads when the work panel is located to have said depression aligned with respect to said plates, and toggle linkage means adapted to actuate said plates successively to have one plate bring the upholstery material all the way to the bottom of the respective depression on the beaded base

panel before the next plate pushes the material into the next depression.

16. A machine for applying substantially unstretchable upholstery material to beaded base panels, said machine comprising a work table adapted to receive a work panel and to locate the same, a plurality of individually slidable plates having work edges adapted when actuated to push the upholstery material into depressions between said beads when the work panel is located to have said depression aligned with respect to said plates, and a corresponding plurality of fluid-operated cylinders operatively connected to said plates and adapted to actuate them successively to have the previous plate bring the upholstery material all the way to the bottom of the respective depression on the beaded base panel before the 15 next plate pushes the material into the next depression.

17. A machine for applying upholstery material to beaded base panels, said machine comprising a work table adapted to receive a work panel and to locate the same, a plurality of individual slidable plates having work 20 edges adapted when actuated to push the upholstery

material into depressions between said beads when the work panel is located to have said depression aligned with respect to said plates, and mechanical means adapted to actuate said plates successively starting at the two middle plates and proceeding successively toward the edges of the panel to have one plate on each side bring the upholstery material all the way to the bottom of the respective depression on the beaded base panel before the next plate pushes the material into the next depression.
